ANTENNA REFLECTORS

Lewis H. Finneburgh, Jr., Cleveland Heights, and Victor W. Trebules, Cleveland, Ohio; said Trebules assignor to said Finneburgh

Application October 4, 1954, Serial No. 459,934

5 Claims. (Cl. 343—915)

This invention relates to radio frequency antennas and particularly to antennas for use to receive television broadcasts. More particularly, the invention relates to reflectors for improving the gain and the "front-to-back ratio" of such antennas.

For most purposes, solid sheet reflectors of appropriate shape, made of an electrically conductive material, are electrically the most efficient. However, they are impractical for most outdoor installations because of their weight and high wind resistance. As a result, so-called "screen reflectors," which closely approach the electrical efficiency of sheet reflectors, have generally been employed instead of sheet reflectors when the reception problems have been sufficiently great to require their use. Screen reflectors of relatively high efficiency may be constructed as an array of spaced parallel rods of electrically conductive material, the array of rods preferably conforming to the contour of a sheet reflector designed for the same purpose. So long as the rods lie in planes parallel to the plane of polarization of the radio frequency waves to be detected and are spaced apart about $\frac{1}{10}$ of a wave length or less for the particular frequency involved, their reflecting characteristics are very close to those of a solid sheet reflector of the same contour.

For television reception in the V. H. F. range, for example, a sufficiently close approximation to the effect of a solid sheet reflector is achieved in most instances with a rod spacing of about six inches. For the most common types of television antennas, a screen reflector should be planar and more or less rectangular in outline, and it should extend in a vertical plane directly behind the driven antenna elements, with the reflector rods extending horizontally. The screen should be at least coextensive laterally and vertically with the driven elements of the antenna and, therefore, must be of substantial area for all types of V. H. F. antennas, particularly multiple bay or stacked antenna arrays.

In the television antenna field, in which antennas are mass produced for shipment to all parts of the country, the cost and structural complexity of screen reflectors and the difficulty of packing, shipping, and mounting them, have greatly limited their use, in spite of their long recognized electrical superiority compared to the more common single rod or tube reflectors. Some of these commercial drawbacks of screen reflectors are obviously inherent in any antenna structure having the large physical dimensions of a screen reflector, and little can be done to minimize them. However, as the number of television broadcasting stations in the United States has increased, interference problems have become more and more acute, particularly in the rural or "fringe" areas. At a given location in these areas, signals of comparable strength from the same or adjacent channels are now commonly receivable from several different directions of the compass. In order to reject undesired signals from the back sides of antennas in these locations, the use of more efficient antenna reflectors has become essential. As a result, the demand for screen reflectors has greatly increased, and

2

the need for more commercially practical screen reflector designs has increased accordingly.

The principal objects of the present invention are to provide a screen reflector for antennas which is relatively inexpensive to manufacture and light in weight, which can be collapsed in a simple manner for packaging in the same carton with the antenna to which it is to be applied, and which can be easily and quickly extended and installed in the field.

10 A more specific object of the invention is to provide a screen reflector in the form of a rectangular array of spaced parallel conductors which can be collapsed in a simple manner so that the maximum dimension of the collapsed structure is no greater than one of the sides of the uncollapsed array.

Another object of the invention is to provide such a collapsible screen reflector having the requisite structural rigidity when installed to resist heavy winds and ice loads.

The invention is characterized by a plurality of supporting strips generally disposed in the same plane in laterally aligned, parallel relationship, and a plurality of rods generally extending transversely to said strips in laterally aligned, parallel relationship in a second plane parallel to the first, each of the rods being attached to each 25 of the strips for rotation with respect thereto about an axis normal to said planes and for individual longitudinal movement with respect to said strips. Such an assembly may be collapsed with a parallelogram folding action, and the individual parallel rods may be slid longitudinally relative to one another so that they are still laterally aligned in the fully collapsed assembly. Conversely, the collapsed assembly may be extended to its normal rectangular form with a parallelogram folding action, and the individual rods may be slid longitudinally relative to 30 one another so that they are laterally aligned in a rectangular array in the fully extended assembly.

Such a reflector structure is particularly desirable when the rectangular screen dimensions are very large in both height and width, since the parallelogram folding action 40 would otherwise result in a substantial increase in the dimension of the collapsed assembly in the direction in which the rods extend. The individual slidability of the rods relative to the transverse supporting strips makes it a simple matter to avoid this by moving the rods into 45 exact lateral alignment in both the extended and collapsed conditions of the assembly. When dimensioned for use with a long collinear antenna, for example, with the reflector rods parallelling the array of driven collinear conductors and being of substantially the same overall length, such a reflector may be collapsed and packaged in a carton 50 with the collinear array without requiring an increase in the carton length to accommodate the reflector. This packaging advantage and the simplicity of the structure 55 and its mode of operation, render the reflectors of the present invention far more practical commercially than any other large screen reflectors with which we are familiar.

The foregoing and additional objects, features, and advantages will be more fully understood and appreciated from the following detailed description of a preferred embodiment of the invention, taken in conjunction with the accompanying drawing, in which:

Figure 1 is a front elevation of a well known type of 60 four-bay collinear antenna to which a screen reflector conforming to the present invention has been applied;

Fig. 2 is an end elevation of the antenna of Fig. 1, the upper part of the mast being broken away for clarity;

Fig. 3 is a fragmentary plan view, on an enlarged 65 scale, of the antenna of Fig. 1;

Fig. 4 is a fragmentary section, on a further enlarged scale, of the reflector structure shown in Fig. 1, the

plane of the section being indicated by the line 4—4 in Fig. 1;

Fig. 5 is a similar sectional view of the same structure, the plane of the section being indicated by the line 5—5 in Fig. 4;

Fig. 6 is an enlarged front elevation of one of four individual reflector units which comprise the entire reflector shown in Fig. 1;

Fig. 7 is a view similar to Fig. 6, but showing the reflector unit collapsed;

Fig. 8 is a further enlarged front elevation of one of the vertically extending supporting strips of the reflector shown in Fig. 1, the view being foreshortened for convenience;

Fig. 9 is a view similar to Fig. 8 of a modified form of supporting strip;

Fig. 10 is a fragmentary vertical section, on an enlarged scale, taken through a pair of vertically aligned supporting strips of two adjacent reflector units of the reflector assembly of Fig. 1, showing how these supporting strips are interfitting and connected together to rigidify the reflector assembly; and

Fig. 11 is a similarly enlarged vertical section taken through one of the vertical supporting strips of the reflector assembly of Fig. 1, showing how the supporting strips of the reflector assembly are secured to the rest of the antenna structure.

Referring to the several views of the drawing, the reflector assembly is illustrated as applied to a four-bay collinear antenna of the type described and claimed in U. S. Patents Nos. 2,566,287 and 2,630,531 of Lewis H. Finneburgh, Jr. Each bay of this form of antenna comprises a relatively large diameter, horizontal, reflector tube 12 constituting an integral part of the antenna structure before application of the screen reflector thereto.

In front of the reflector tube 12 and parallel therewith, is an array of three collinear, half-wave, driven conductor elements, including a central conductor element 13 having a central gap therein and identical outer conductor elements 14. These driven elements are supported by three identical inner insulators 16 and two outer insulators 17 of different form from the insulators 16. The insulators 16 and 17 are in turn respectively supported on the forward ends of a corresponding number of horizontal tubular arms 18, and the opposite ends of the tubular arms 18 project into the interior of and are rigidly secured to the reflector tube 12 by machine screws 19 (Figs. 3 and 11).

Each reflector tube 12 is secured to a vertical mast 21 by means of a conventional U-bolt 22 and saddle 23 (Figs. 2 and 3) so that the reflector tube 12 is restrained against rotation about its own axis. Thus, the reflector tube 12 holds the tubular arms 18 so that they extend horizontally as cantilever beams to carry the driven conductor elements 13 and 14.

The driven conductors 13 and 14 of each bay are connected for in-phase operation by quarter-wave shorted stubs. Each pair of corresponding stubs in the two upper bays has a common, horizontal, shorting conductor 25 and pairs of identical vertical legs 26. Each pair of corresponding stubs in the two lower bays is similarly constructed.

The upper two bays of driven conductors 13 and 14 are also connected together by 2 pairs of identical, vertical, feeder conductors 27, the two pairs of feeder conductors being respectively connected to the central collinear elements 13 of these bays, on opposite sides of the central gap therein. The lower two bays of driven conductors are similarly connected by an identical pair of vertical feeder conductors 27.

Insulators 28 hold the feeder conductors 27 of each pair in spaced parallel relationship, and the upper and lower pairs of feeder conductors 27 between two bays are connected together and to the associated insulator 28

by pivotal joints 29, which provide connections for suitable additional conductors (not shown for simplicity) which electrically connect the upper two bays of driven conductors to the lower two bays of driven conductors and to a conventional two-conductor transmission line (also not shown for simplicity).

The above described antenna structure is rendered collapsible into a compact form for packaging by additional pivotal joints 30, the axes of all of the pivotal joints 29 and 30 being horizontal and normal to the common plane of the four bays of driven conductors. Thus, each pair of bays connected by vertical conductors 26 and 27 may be collapsed together, the several pairs of conductors 26 and 27 swinging with a parallelogram motion in the plane of the 4 bays of driven conductors.

The above described antenna structure is more fully disclosed in the above mentioned prior patents of Lewis H. Finneburgh, Jr., and is disclosed herein only in such detail as seemed desirable in order to explain the application thereto of the screen reflector to which the present invention relates. The above described antenna structure per se forms no part of the present invention and is disclosed herein only as one illustration of a suitable use for the present invention. It will be apparent that the screen reflector hereinafter described may also be applied to other forms of antennas with the same or similar advantages.

The screen reflector of the present invention, when designed for use with a large, four bay, antenna such as has been described above, is preferably made in a plurality of smaller sections adapted to be individually collapsed and connected together when extended for use. One such smaller section or unit is illustrated in front elevation in Fig. 6 in its extended position with the reflector tube 12 of the antenna shown in phantom outline in the relationship thereto which it occupies in the completed assembly shown in Figs. 1, 2, and 3.

As shown in Fig. 6, the single reflector unit comprises a plurality of parallel supporting strips 32, extending vertically in the drawing. These strips 32 are preferably channel-shaped in cross-section, as shown in Figs. 3 and 4, so that they are relatively rigid yet light in weight. The supporting strips 32 are in lateral alignment with each other and lie substantially in a common vertical plane.

A plurality of transversely extending metal rods 33 are disposed in spaced apart, parallel relationship and are in lateral alignment with each other substantially in a second vertical plane. The plane of the array of rods 33 is parallel with and close to the plane of the supporting strips 32, each rod 33 being disposed against each strip 32 and attached thereto for relative rotation about axes normal to said planes and also for longitudinal sliding movement of the rods with respect to the supporting strips.

The securing of the rods 33 to the supporting strips 32 so as to permit both the rotation and sliding of the rods relative to the supporting strips may be by any suitable form of bracket or clip. However, a particularly desirable form is that illustrated in Figs. 4 and 5. As shown therein, the bottom or base portion of each channel 32 is provided with an aperture 34 opposite each rod 33. A generally U-shaped clip 36, having outwardly turned end portions 37, has its closed end projecting through one of the apertures 34 and around the oppositely located rod 33. A small helical spring 38 surrounds the legs of the clip 36 and is held under axial compression against the inside surface of the base of the channel 32 by the end portions 37 of the clip, thereby holding the rod 33 snugly against the base portion of the channel. As is apparent, the rod may be slid longitudinally while so embraced by the legs of the clip. Since the clip may rotate about the axis of the aperture 34, this also permits the rod 33 to rotate about this same axis relative to the strip 32.

Each rod 33 may be secured to each strip 32 in this

manner by threading the individual clips 36 through their springs 38 and then through their apertures 34 and forcing them in the spring-compressing direction while sliding the rods 33 through the clip loops. It is a simple matter to hold all of the individual clips and springs in this manner in a suitable jig while sliding the rods into their secured positions one after another, or simultaneously, as may be desired.

The resulting assembly shown in Fig. 6 may obviously be collapsed or folded with a parallelogram action, and, by sliding all of the rods longitudinally in one direction or the other, produce the collapsed relationship of the assembly shown in Fig. 7, rather than an elongated collapsed assembly in which the rods are staggered in laterally offset relationship relative to one another. As indicated in phantom outline in Fig. 7, this permits the collapsed assembly to be contained within a container outline 39 of substantially the length of an individual rod 33.

As shown in Fig. 6, each screen reflector unit may comprise, say, four rods 33 spaced uniformly apart except for a greater spacing between the centermost pair of rods to accommodate the reflector tube 12 of the antenna, which serves electrically as an additional rod 33 while also serving mechanically to support the screen unit. Each supporting strip 32 has an additional aperture 34 therethrough at its mid-point opposite the reflector tube 12. Each supporting strip 32 may be disposed opposite the axis of a tubular arm 18 of the antenna, and the machine screw 19 may be passed through this additional aperture 34 and through the wall of the reflector tube 12, and be threaded into the aligned tubular arm 18. This permits all of the supporting strips 32 to pivot at their mid-points about the machine screws 19 which secure them to the reflector tube 12. Thus, the screen reflector unit of Fig. 6 may be collapsed as shown in Fig. 7 while secured to the reflector tube 12 in the manner described.

The reflector tube 12 of each bay of the antenna shown in Figs. 1, 2, and 3 may have a screen reflector unit secured thereto and collapsed therewith. The supporting strips 32, of one unit, when the four units are opened up to their normal positions, overlap respectively with the corresponding supporting strips of the adjacent unit or units and interfit therewith as shown in Fig. 10. Slots 42 may be formed in the end portions of each supporting strip 32 to receive machine screws 43 for securing overlapped supporting strips together with relative longitudinal adjustability. When the supporting strips 32 are all secured together in this manner, the complete assembly of antenna and screen reflector results as shown in Fig. 1.

For convenience in mounting screen reflector units on an antenna in the field, a key-hole shaped aperture 34a may be formed at the mid-point of each supporting strip 32a, as shown in Fig. 9, instead of a round aperture 34. By backing off four machine screws 19 in the reflector tube 12 of each antenna bay, the enlarged portions of the four key-hole apertures 34a of the four supporting strips 32a of a single unit may be slipped over the heads of the machine screws. The reflector unit may then be slid downwardly until the shanks of the machine screws are embraced by the narrower portions of the key-hole apertures 34a. Tightening of the machine screws 19 then securely mounts the reflector unit, and the four reflector units may be secured one to another, the same as described above.

With the particular collapsible antenna shown in Figs. 1, 2, and 3, the collapsing actions of the screen reflector units and of the antenna per se are such that the antenna and four screens attached thereto may all be folded to-

gether into a single, compact, collapsed unit for packing in the same carton. However, whether the individual reflector units are assembled on and packaged with an antenna or are separately packaged, the space saving manner in which they may be collapsed has essentially the same packaging advantages.

From the foregoing description, it will be seen that the screen reflector of the invention accomplishes the various objects of the invention in a simple and commercially practical manner, thus greatly reducing the objectionable features of large screen reflectors which have heretofore limited their use in the television antenna industry.

Having described our invention, we claim:

1. A reflector for radio frequency antennas comprising a plurality of parallel supporting strips normally extending vertically in horizontally spaced, laterally aligned relationship substantially in a first common plane, a plurality of transversely extending metal rods disposed in a spaced-apart parallel array in a second common plane parallel to said first common plane, means attaching each of said rods to each of said strips for rotation with respect thereto about an axis normal to said planes and for longitudinal movement of the rods with respect to said strips, whereby the assembly may be collapsed for packaging with the rods laterally aligned with each other, and the parallelogram outline of the array of rods when the assembly is unfolded for use may be adjusted to a rectangular array by longitudinal sliding of the rods relative to each other and to said strips.
2. A reflector according to claim 1 in which each of said rods is attached to each of said strips by a U-shaped clip whose legs straddle the rod at the closed end of the clip, the legs of the clip at the open end thereof passing through an aperture in the strip and being secured therein by lock means on the opposite side of the strip from the rod.
3. A reflector according to claim 1 in which each of said rods is attached to each of said strips by a U-shaped clip whose legs straddle the rod at the closed end of the clip, the legs of the clip at the open end thereof passing through an aperture in the strip and being secured therein by lock means on the opposite side of the strip from the rod, said lock means comprising a spring for yieldingly pulling the closed end of the clip against the rod and the rod against the strip.
4. A reflector according to claim 1 in which each of said rods is attached to each of said strips by a U-shaped clip whose legs straddle the rod at the closed end of the clip, the legs of the clip at the open end thereof passing through an aperture in the strip and being secured therein by lock means on the opposite side of the strip from the rod, said lock means comprising a helical spring under axial compression for yieldingly pulling the closed end of the clip against the rod and the rod against the strip, the legs of the clip having reversely bent free ends that project through the spring and are hooked over the adjacent end turn thereof.
5. A reflector according to claim 1 in which said strips are of channel shape in cross-section and project endwise beyond said rods for interfitting with corresponding strips of a second like assembly to provide double the reflector area of one such assembly, and means for securing interfitted ends of the strips together.
